UNITED STATES PATENT OFFICE.

WALTER H. WHITTIER AND FRANK J. M. CURRAN, OF GRAND RAPIDS, MICHIGAN,
ASSIGNORS TO GRAND RAPIDS REFRIGERATOR COMPANY, OF GRAND RAPIDS,
MICHIGAN, A CORPORATION OF MICHIGAN.

SHELF-SUPPORT FOR REFRIGERATORS.

1,291,321.

Specification of Letters Patent. Patented Jan. 14, 1919.

Application filed March 23, 1918. Serial No. 224,373.

To all whom it may concern:

Be it known that we, WALTER H. WHITTIER and FRANK J. M. CURRAN, citizens of the United States of America, residing at 5 Grand Rapids, in the county of Kent and State of Michigan, have invented certain new and useful Improvements in Shelf-Supports for Refrigerators; and we do hereby declare the following to be a full, clear, and 10 exact description of the invention, such as will enable others skilled in the art to which it appertains to make and use the same.

This invention relates to a shelf support for refrigerators, the same consisting of a 15 novel construction of support which may be attached to the sides of sheet metal linings of provision compartments of refrigerators and on which shelves may be placed to carry the various articles placed in provision compartments. It is a primary object and purpose of our invention to make a novel shelf-supporting device from sheet metal having substantially the same thickness of metal as that of the lining to which a plurality of said 20 supports are connected, and to attach the supports in a novel manner with a resultant economy in manufacture, whereby the production of a refrigerator lining is secured which may be readily coated with porcelain 25 on the inner sides thereof, and the same baked to uniformly cover the inner sides of the lining and the shelf supports which project therefrom, it being possible to attain a substantially even temperature in the lining 30 and supports due to the fact that the metal of the lining and of the shelf supports are of substantially the same thickness.

For an understanding of the invention, reference may be had to the accompanying 40 drawing illustrating a preferred embodiment thereof, in which:

Figure 1 is a perspective view of a refrigerator lining equipped with a plurality of the shelf supports of the invention.

Fig. 2 is a fragmentary vertical section 45 substantially on the line 2—2 of Fig. 3.

Fig. 3 is a view of a fragmentary portion 50 of the lining looking against the outer side thereof and showing the attachment of a shelf support, and

Fig. 4 is a plan of the blank of sheet metal from which the shelf support is made.

Like reference characters refer to like parts in the different views of the drawing.

Linings for refrigerators in many instances are of sheet metal and in Fig. 1 we have indicated one form of provision compartment lining for refrigerators comprising vertical sides 1, a back 2, top 3, and bottom 4, the front being open for access to the provision compartment. At spaced apart intervals in the height of the sides 1 shelf supports 5 are secured, projecting inwardly as shown, certain of the shelf supports on each side being disposed in substantially the same horizontal plane so that shelves may be located and held horizontally thereon, it being evident that a number of shelves may be thus supported one above the other.

The shelf supports 5 in our invention are 70 formed from sheet metal having substantially the same thickness as the metal of the lining. These supports are of cylindrical form, being pressed and formed of a single piece of sheet metal, and being closed at one end, while at the other end oppositely extending ears 6 are formed such that when the cylindrical portions of shelf supports with the closed ends thereof are inserted through suitable openings in the vertical 80 sides of the lining, the ears 6 lie flat against the outer surface of said vertical sides of the lining adapting the same to be readily attached to the lining, as indicated at 7, by spot welding. In practice the spot welding 85 method of attachment is used, preferably, though it is to be understood that any other suitable means of securing or holding the shelf supports in place may be used. For instance in cheaper makes of refrigerators 90 the supports may be merely inserted through openings in the lining to bring the ears against the outer sides of the lining, and held in position by portions of the refrigerator structure afterward built around and enclosing the lining. The blank 8 from which each shelf support is made is of the form shown in Fig. 4, the central portion thereof being utilized to make the closed end of a shelf support, the sections diverging therefrom being formed into substantially semi-cylindrical portions the edges of which meet, thus making a complete cylindrical member, while the ends 6 are bent in opposite directions to form the attaching ears.

A shelf support of this character is readily blanked and formed from sheet metal being made completely by stamping opera-

tions at a very low cost of manufacture. The same are readily attached to refrigerator linings and when attached as described, are positively connected so that no separation from the lining can take place. One important feature of the invention resides in the fact that after attachment to a lining, the inner side of the lining and the outer cylindrical portions, together with the closed ends of the shelf supports may be coated with porcelain and the same baked thereon in a uniform and even manner, this being due to the fact that all of the metal to which the porcelain is applied is of substantially uniform thickness and takes a substantially uniform degree of heat in the baking oven. With solid shelf supports of the same form riveted or otherwise secured in place on the vertical sides of the lining, uniformity in temperature of the same with the sides, back, top and bottom of the lining is practically impossible to attain, resulting many times in an imperfect covering particularly as regards uniformity of the covering on the inner sides of the lining with the covering on such solid shelf supports, or at the juncture of the lining and supports. Our invention permits this important advantage as well as being advantageous from the standpoint of economy of manufacture and production of a better combined lining and shelf support whether or not the inner sides of the lining are to be covered with porcelain.

35 We claim:

1. In combination with a sheet metal refrigerator lining, of a shelf support projecting inwardly from a side of the lining, said support being of hollow cylindrical form closed at one end and made from sheet metal, and oppositely projecting ears at the

other end of the support, said cylindrical portion of the support being passed through an opening in the lining to bring said ears against the lining, whereby the same may be permanently connected to the lining, substantially as described. 45

2. A shelf support adapted for use with refrigerators and adapted for attachment to sheet metal linings of refrigerators, comprising a hollow cylindrical body formed from sheet metal and closed at one end, and oppositely projecting ears at the opposite end of the body, substantially as and for the purpose described. 50

3. In combination with a sheet metal refrigerator lining, a sheet metal shelf support formed from a single piece of sheet metal of substantially the same thickness as the lining, said support comprising a hollow cylindrical body closed at one end and provided with oppositely extending ears at the other end, said cylindrical portion of the support being passed through an opening in a side of the lining thereby bringing the ears against the outer side of the lining, and electric welding connections between said ears and the lining, substantially as described. 55

4. A shelf support adapted to be secured to sheet metal refrigerator linings, formed from a single length of sheet metal bent back upon itself at the center thereof and formed as a hollow cylindrical body with a closed end, and oppositely projecting ears 75 at the opposite end of the body, substantially as and for the purpose described. 70

In testimony whereof we affix our signatures.

WALTER H. WHITTIER.
FRANK J. M. CURRAN.
